WORK SUIT FOR FARMERS

Ralph J. Schaeffer, Ferdinand, Idaho

Application August 4, 1950, Serial No. 177,655

2 Claims. (Cl. 2-2)

1

This invention relates to a work suit for farmers and more particularly to a work suit for farmers which prevents the farmer from being adversely affected by fine chaff and dust during completion of his farm labors.

An object of this invention is the provision of a work suit for farmers which is airtight and dust-free, but which does not interfere with the farmer's operation.

A further object is to provide a work suit for farmers having means for air-conditioning the interior of the suit.

Another object is the provision of a work suit for farmers which may be readily donned or removed by the farmer.

Still another object of this invention is the provision of a work suit for farmers which is simple and economical of construction, requiring a minimum number of parts, but which permits the farmer to operate in an air-conditioned atmosphere.

A still further object is to provide a work suit for farmers in which the helmet and hand coverings are readily and rapidly removable without interfering in the air-conditioning or the dust-free operation of the suit.

The exact nature of this invention as well as other objects and advantages thereof will readily be apparent from consideration of the following detailed description relating to the annexed drawings in which:

Figure 1 is a front elevational view of the work suit of the present invention, together with a diagrammatic view of the air-conditioning apparatus;

Figure 2 is a side elevational view of the work suit of Figure 1;

Figure 3 is an enlarged front elevational view, partly in section, of the helmet of Figure 1;

Figure 4 is a front elevational view of the breast plate of the suit of Figure 1;

Figure 5 is an enlarged side elevational view, partly in section, of the arm and glove of the suit, illustrating one form of attaching and sealing means according to this invention;

Figure 6 is a fragmentary perspective view, illustrating the leg and foot connection of the suit of Figure 1;

Figure 7 is an enlarged fragmentary view, partly in section of the breast plate of Figure 4, illustrating the mode of attachment of the garment to the breast plate;

Figure 8 is an enlarged elevational view of the mouthpiece of the helmet;

Figure 9 is a side elevational view of a portion

of the air-conditioning apparatus of Figure 1, illustrating its mode of attachment to a farm implement;

Figure 10 is an enlarged perspective view of the mounting clamp of Figure 9; and

Figure 11 is a view similar to Figure 5 illustrating a modified form of attaching means.

Referring now to the drawings, wherein like reference characters designate like or corresponding parts throughout the several views, there is shown in Figure 1 the suit of the present invention which comprises a garment, generally designated 11, a helmet 12 and a breast plate 13.

Garment 11 is made of any suitable flexible air tight material, such as rubber or a rubberized material. Garment 11 comprises a body portion 14, arm portions 15 and leg portions 16. Detachably secured to the free end of each arm portion 15 is a glove 17, preferably made of a material similar to that of garment 11. As shown in Figure 5, glove 17 is secured to arm portion 15 by means of a zipper 18. In order to make the connection or joint between arm portion 15 and glove 17, a cover or flap 19 is secured to portion 15 and overlaps the joint, flap 19 being provided with an elastic band, not designated, which tightly fits around glove 17.

In a modified form of glove attachment, as illustrated in Figure 11, glove 17 is provided with an elasticized cuff 18' which extends over the elasticized cuff portion, not designated, of arm portion 15'. A flap 19' similar to flap 19, seals the joints.

A leg connector 21, which fits around the shoe 22 of the wearer as shown in Figures 1 and 2, is detachably secured to leg portion 16 by any suitable means, such as slide fastener 23, there being a flap 24, similar to flap 19, connected across the joint between leg portion 16 and connector 21. In this manner, the suit remains airtight and dust-free when donned by the wearer. Furthermore, if either gloves 17 or leg connector 21 are removed, the suit remains airtight since the elastic band will tightly grip the hand or shoe of the wearer.

In order to enable the wearer to readily don or remove the suit, a slide fastener 25 is centrally mounted along the full length of the front of body portion 14, as shown in Figure 1. As shown in Figure 1, one end 26 of body portion 14, overlaps the other, and is secured to this other end by any suitable means, such as snap fasteners 27. In this manner, the suit is maintained airtight after being donned by the wearer. If desired, pockets 29 may be included with the suit.

To provide a simple and airtight connection between garment 11 and helmet 12, breast plate 13 is mounted on the shoulders of the wearer, as shown in Figures 1 and 2. Plate 13 comprises a collar 31, which is adapted to encircle the neck of the wearer, and a support 32. Support 32 is preferably made flexible, in order to permit the wearer to don as much clothes as he desires. Support 32 is provided with a plurality of perforations 33, for better circulation of the air, and a pair of strap slots 34 for receiving straps 35 which support garment 11 on the shoulders of the wearer. A belt 36 is provided for the exterior of the suit.

To form the seal between plate 13 and the upper open end of body portion 14, an indented peripheral channel 37 is provided in plate 13 intermediate collar 31 and support 32. The upper end of portion 14 is provided with a draw string 38, which, when drawn tightly, pulls portion 14 into channel 37 thereby sealing the open end of the suit, as shown in Figure 7. In this manner, plates 13, which are preferably made of plastic, may be constructed in different sizes to accommodate different wearers, while the same garment may be used for more than one wearer.

Collar 31 is provided with a threaded portion 39 at the upper end thereof which receives the threaded portion, not designated, of helmet 12 to thereby detachably secure helmet 12 to plate 13. To form an airtight seal at the joint between helmet 12 and plate 13, a flap 41, similar to flap 19 is secured to helmet 12, as shown in Figures 1 and 2.

Helmet 12 is made of a light-weight material, preferably plastic, and may be entirely transparent. A pair of handles 42 are mounted on helmet 12 in order to make the helmet more readily removable. A sun visor 43 is mounted on helmet 12 by means of bolts 44, visor 43 being adjustable about bolts 44 and held in place by friction.

Helmet 12 is provided with a cushion 45 in order to cushion the head of the wearer, as shown in Figure 3. Space 46 is provided in the upper end of helmet 12 to receive a radio receiver 47, which may be mounted in any suitable manner, as by bolts 48. A mouthpiece 51 may be provided in the front end of helmet 12 to permit the insertion of a cigarette holder 53. As shown in Figure 8, mouthpiece 52 comprises a plurality of flexible baffles 28, preferably made of rubber, lying in contiguous relation to each other. Cigarette holder 52 is inserted at the junction point of all the baffles 28. In this manner, the helmet remains dust-free and airtight.

In order to permit the interior of garment 11 to be air conditioned, a four-way permanent hose connection 53 is provided in body portion 14 in the upper end thereof, one arm 54 of connection 53 extending through portion 14 to one arm of a Y-type connector 55. The other arm of connector 55 is coupled to an air intake tube 56 which extends into collar 31 to supply air to the interior of helmet 12.

An air hose 57 is connected to one arm of connection 53 and extends downwardly through arm portion 15. An air hose 58 is connected to another arm of connection 53 and extends downwardly through body portion 14 and leg portion 16 of garment 11. The remaining arm of connection 53 is a two way hose 61, the ends of which terminate in arm portion 15 and leg portion 16, respectively. By positioning the open ends of the air hoses adjacent the lower ends of

portion 15 and 16, the fresh air will enter at the lower ends of the garment, while the warmer stale air will rise and be exhausted through exhaust valves 62 in the upper end of body portion 14. Similarly the stale air in the helmet 12 will exhaust through exhaust valve 63 in the upper end thereof.

The air conditioning apparatus of the present invention, as shown diagrammatically in Figure 10, comprises a pre-cleaner or filter 64 coupled by means of tube 65 to a liquid air cleaner 66. Filter 64 is mounted a considerable distance above cleaner 66 in order to be out of the path of the dust. Cleaner 66 is preferably filled with an odorless liquid, such as water.

Cleaner 66 is connected by means of tube 67 to a fan 68 which is supplied with power overlines 69 from any suitable source, such as storage battery 71. Fan 68 propels the clean air through tube 72 and flexible hose 73 to connector 55.

Cleaner 66 is provided with a bracket 74, as shown in Figures 1 and 9, bracket 74 having a depending leg, not designated, which is mounted on any suitable farm implement 25 by means of mounting clamp 76. As shown in Figure 10, mounting clamp 76 is triangular in shape and has an upstanding V-shaped flange 77. Clamp 76 is mounted on implement 25 by any suitable means with the apex of flange 77 downward. The depending leg of bracket 74 slides into flange 77 thereby providing an efficient and quickly detachable connection between cleaner 66 and implement 75.

If desired, a 6-volt heating element, which may conveniently be operated from battery 71, may be mounted in garment 11, or in the air conditioning apparatus, for the purpose of heating the suit.

It is believed to be an important characteristic of the invention that a joint structure is provided between the helmet and the flexible garment body portion, that is relatively inexpensive, is effective to form a substantially air-tight joint therebetween, and permits ready removability of the helmet, while holding the helmet in proper position over the head of a wearer whenever the suit is in use. To this end, the joint structure includes the breast plate mentioned above, that is formed at its lower end with a support proportioned approximately to the contour of the shoulders, upper chest, and upper back portions of the wearer's body, an intermediate portion having the circumferential channel 37, and an upstanding collar threaded to effect a separable connection with the lower end of the helmet, said lower end of the helmet being concentric with the collar and the separable connection in question being removed from the channel, so that the helmet can be removed without interfering with the attachment of the flexible garment body portion to the breast plate. With reference to the attachment of the garment body portion to the breast plate, a flexible member, comprising the drawstring 38, is attached to the upper end of the garment, and contracts said upper end of the garment to the inner diameter of the channel 37 for snug engagement between the breast plate and garment, after which the ends of the drawstring are tied in the manner illustrated in Figure 1.

It should be understood, of course, that the foregoing disclosure relates to only a preferred embodiment of the invention and that numerous modifications or alterations may be made therein without departing from the spirit and the

scope of the invention as set forth in the appended claims.

What is claimed is:

1. In an air-conditioned suit, a joint structure for effecting a substantially airtight connection between a helmet of rigid formation and a flexible garment portion having a chest covering portion provided in its upper end with a neck opening having a loop extending peripherally around said opening, comprising a breastplate integrally formed to include a support at the lower end thereof extending through said loop and underlying the chest covering portion of said garment body portion and proportioned to fit over and be supported upon the shoulders, upper chest, and upper back portions of the body of a wearer, an intermediate portion having a circumferential channel of substantially circular cross section and having a circumferential slot providing communication between said channel and the exterior of said intermediate portion, and an upstanding rigid collar at the upper end thereof concentric with and receiving the lower end of said helmet; a draw string extending through said loop and disposed within said channel to draw the loop through the slot into the channel and thereby contract said upper end of the garment body portion to the inner diameter of the channel for snug engagement with the breast plate; and means spaced from the channel and draw string separably connecting said collar and the lower end of the helmet.

2. In an air-conditioned suit, a joint structure for effecting a substantially airtight connection between a helmet of rigid formation and a flexible garment body portion having a chest covering portion provided in its upper end with a neck opening having a loop extending periph-

erally around said opening, comprising a breastplate integrally formed to include a support at the lower end thereof extending through said loop and underlying the chest covering portion of said garment body portion and proportioned to fit over and be supported upon the shoulders, upper chest, and upper back portions of the body of a wearer, an intermediate portion having a circumferential channel of circular cross section and having a circumferential slot providing communication between said channel and the exterior surface of said intermediate portion, and an upstanding, threaded, rigid collar at the upper end of the breast plate concentric with and receiving the lower end of said helmet, said lower end of the helmet being threaded for detachable connection to the collar; and a draw string extending through said loop and disposed within said channel to draw the loop through the slot into the channel and thereby contract said upper end of the garment body portion to the inner diameter of the channel for snug engagement with the breast plate, said draw string being disposed in spaced relation to the threaded connection between the helmet and collar.

RALPH J. SCHAEFFER.
